SWINGING MECHANISM FOR BOOMS OF EXCAVATING-MACHINES.

1,169,836.

Specification of Letters Patent.

Patented Feb. 1, 1916.

Application filed November 10, 1913. Serial No. 800,074.

To all whom it may concern:

Be it known that we, CHARLES B. KING and BENJAMIN JACOBY, citizens of the United States, residing at Marion, in the county of Marion and State of Ohio, have invented 5 certain new and useful Improvements in Swinging Mechanism for Booms of Excavating-Machines, of which the following is a specification, reference being had therein 10 to the accompanying drawing.

This invention relates to swinging mechanism for booms of excavating machines. In machines of this character there is a strong endwise thrust imposed upon the 15 drum during the swinging of the boom and much difficulty has been experienced in holding the drum against longitudinal movement on its shaft and, if the drum is successfully locked to the shaft, in preventing the spring- 20 ing of the frames in which the shaft is mounted, which would throw the bearings out of alinement and interfere with the operation of the other mechanism mounted upon the frame.

25 The object of the invention is to provide means whereby the drum will be securely held against endwise movement and the frame members held against displacement due to the thrust imposed thereon by the 30 drum and its shaft.

In the accompanying drawings, Figure 1 is a side elevation of the frame supporting the swinging drum; Fig. 2 is a horizontal sectional view taken through the drum and 35 the bearings therefor; and Fig. 3 is a detail view of the bearing face of one of the caps.

In these drawings we have illustrated our invention as applied to the swinging mechanism of a well known form of steam shovel. 40 As here shown this mechanism comprises a drum 1 about which extends a cable 2 which is connected with and imparts swinging movement to the boom, the latter not being shown. The drum 1 is mounted upon a shaft 45 3 which is journaled in bearings 4 in the frame members 5. These frame members are of considerable height, to accommodate the mechanism which is mounted thereon, and the bearings for the shaft 3 are formed 50 in the uppermost portions thereof. The drum 1 has secured thereto a gear 6 which meshes with a pinion 7 on a shaft 8 also journaled on the frame members 5 and driven

from a suitable engine which is not here shown.

As the cable 2 travels toward the end of the drum an endwise thrust is imposed upon the drum and this thrust imposes a severe strain upon the fastening devices by means of which the drum is held in place on its 55 shaft. To effectually resist the tendency of the drum to move lengthwise of the shaft spacing sleeves or collars 9 are interposed between the ends of the hub of the drum and the adjacent frame members 5, thereby 60 interposing a rigid connection between the ends of the drum and the frame members which will prevent the relative movement of these parts lengthwise of the shaft. This connection, however, is such that the strain 65 imposed thereon is transferred to the frame members and as a result the frame members themselves may be sprung apart, the displacement sometimes amounting to as much as a quarter of an inch. Obviously, such 70 displacement of the frame members throws the bearings badly out of alinement and interferes with the operation of all the mechanisms carried by the frame members. To hold the frame members against displacement we have utilized the rotating shaft 75 itself and have provided the same on its outer ends with caps or locking plates 10 which are rigidly secured to the respective ends of the shaft and held against rotation relatively 80 thereto. The frame members are provided with bearing surfaces against which the caps 10 bear and the faces of the caps may be provided with oil grooves 11 to lubricate this bearing surface.

90 It will be apparent, therefore, that by means of this construction we very effectually tie together the several parts of the mechanism and prevent all relative movement of these parts lengthwise of the shaft. 95 The arrangement is such as to oppose a very rigid construction to the lengthwise thrust on the drum. The spacing collars completely fill the spaces between the hub of the drum and the respective frame members and the frame members are firmly held in engagement with the respective collars by means of the holding devices or caps 10 on the ends of the shaft. Consequently, when a thrust 100 is imposed upon the drum the movement of the drum toward the frame member is pre- 105

vanted by the spacing collar and the thrust which is imposed upon the frame member is received by the shaft and transmitted in part to the other frame member, and it will be observed that the construction is such as to not only tie together the frame members but to distribute the strain between the two frame members. Thus, we have very effectually overcome the tendency of the drum 10 to travel along its shaft and the tendency of the frame members to spread.

While we have shown and described one embodiment of our invention it will be understood that this has been chosen for the 15 purposes of illustration only and that we do not desire to be limited to the details of construction shown and described, for obvious modifications will occur to a person skilled in the art.

20 Having thus fully described our invention, what we claim as new and desire to secure by Letters Patent, is:—

1. In a mechanism of the character described, a fixed frame having supporting 25 members, a shaft mounted on said supporting members, a drum mounted on said shaft, a cable wound about said drum and arranged to exert an axial thrust thereon, means carried by said shaft and in engagement with 30 said drum and frame to prevent the axial movement of said drum, and means comprising said shaft to prevent the springing apart of said supporting members due to the re-

sulting thrust against said frame and to divide said thrust between the two supporting members. 35

2. In a mechanism of the character described, a fixed supporting frame having bearings, a shaft mounted in said bearings, a drum mounted on said shaft, a cable wound about said drum and arranged to exert an axial thrust thereon, spacing sleeves fitting snugly between the ends of said drum and the supporting frame, and plates secured to the respective ends of said shaft and bearing 40 against the outer sides of said frame. 45

3. In a mechanism of the character described, a fixed frame having supporting members, bearings in said supporting members, a shaft mounted in said bearings, a drum mounted on said shaft, a cable wound about said drum and arranged to exert an axial thrust thereon, spacing means fitting snugly between said drum and the supporting frame, and means secured to the respective ends of said shaft to prevent the springing apart of the bearings and insuring that the endwise thrust on said drum will be divided between the two frame members. 50

In testimony whereof, we affix our signatures in presence of two witnesses.

CHARLES B. KING.
BENJAMIN JACOBY.
